UNITED STATES PATENT OFFICE.

EMILE BOESCH, OF SAN FRANCISCO, CALIFORNIA.

LAMP.

SPECIFICATION forming part of Letters Patent No. 576,716, dated February 9, 1897.

Application filed September 10, 1894. Serial No. 522,625. (No model.)

To all whom it may concern:

Be it known that I, EMILE BOESCH, a citizen of the United States, residing in the city and county of San Francisco, State of California, have invented an Improvement in Lamps; and I hereby declare the following to be a full, clear, and exact description of the same.

My invention relates to certain improvements in car-lamps of that class which is fixed in the side or end of the car and adapted to give light upon two or more sides. It is also applicable to light streets or houses, with various forms of burners, known as "Argand" or "chimney" burners, either for oil or gas.

It consists in certain details of construction, which will be more fully explained by reference to the accompanying drawings, in which—

20 Figure 1 is a vertical section taken through the lamp, showing its attachment in the end of a car so as to light the interior and also the platform from opposite sides. Fig. 2 is a view showing the application to an Argand gas-burner.

One of the objects of my present invention is to provide a lamp or lantern frame without casing, globe, or door, open at the upper end to connect with the feed-air, which is supplied 30 from above, and having a passage or passages whereby the air is conveyed to a point around or below the lamp and delivered upwardly to the burner. It also contemplates a construction of the feed and exhaust air passages in 35 such a way that the two bodies of air are united, so as to balance any irregularities or variations of pressure caused by the wind or arising from other sources.

When exposed to draft, chimney-burners 40 for oil or gas have heretofore been protected by a casing of metal and glass, or glass entirely, like a globe, but they are apt to smoke or go out under strong draft or a gale of wind, and the same result occurs in burners which 45 are used without a chimney and protected by a casing or globe.

In my improved reflector-lamp I have shown the invention as adapted for use upon a street-car; but the improvements may be used in 50 any connection where they are available.

A is a lantern-body which is made, as shown in the present case, of sufficient size to receive

the oil-fount and chimney, and this body is adapted to be secured to the interior of the woodwork of the car. A hole of sufficient diameter is made through the side of the car, and the part A', which is of smaller diameter than A, passes through the woodwork and incloses an opening through which the light of the lamp is directed upon the platform exterior to the car. Between the two parts A A' is the conically-shaped reflector C, which faces the interior of the car and is inserted level with the woodwork, so that a chimney and burner-socket only project beyond. Within 65 this annular reflector-rim is formed a passage D, which serves to allow the air from above to pass down around the exterior of the reflector and to be delivered to the bottom around the base and oil-fount E of the lamp, and from 70 this point the air is delivered up through the interior of the wick-tube and also within the chimney exterior to the wick-tube, so as to provide a supply of already-heated air for the combustion of the oil.

In the present case I have dispensed with all inclosing glass bodies exterior to the lamp, and thus avoid the obstruction of such glass, as well as the difficulty of obtaining access to the lamp.

The oil-fount E is placed into and over the burner-socket.

The burner F is surmounted by a glass chimney G, the base of which rests upon a soft washer of any suitable material, which 85 serves to form a tight joint to prevent the entrance of air directly around the base of the chimney from the outside, and also forms a cushion H to prevent the breakage of the chimney by sudden shake or jar.

I are springs which press slightly against the exterior of the chimney to steady it and assist in retaining it in place.

A perforated cylindrical screen J surrounds the burner, and through this the air, which 95 is admitted from below, is delivered around the burner.

The upper end of the chimney G connects with the extension-chimney K by means of a funnel-shaped flaring mouthpiece K', into 100 the diverging open end of which the upper end of the chimney is adapted to fit, the diameter of this funnel being such that it will accommodate itself to chimneys of various

sizes. This extension-chimney K slides within an exterior guiding-tube L of sufficiently larger diameter to allow it to move freely. This tube is enlarged, as shown at L', and 5 has an intermediate shoulder against which the upper end of a spiral spring M presses, while the lower end of the spring rests in an outwardly and upwardly turned flange in the bottom of the cone K', so that the spring ex- 10 erts a pressure upon the extension-chimney K to retain the funnel K' constantly in contact with the upper end of the chimney.

Exterior to the extension-chimney K and the guide-tube L is a concentric air-passage 15 formed by a tube N of large diameter, which incloses the upper part of the extension K, and the guide-tube L, extending downwardly around them, and from the upper part of the tube N a funnel-shaped hood O extends outwardly and downwardly, this again being 20 surmounted by a cap P, as shown.

The whole is fixed upon the top of the car and supported by an exterior flanged tube Q.

Openings or passages R admit air around 25 the exterior shell, between the hood O and the deflecting-flange R', allowing it to pass upwardly, as shown by the arrows, through openings in the upper end of the tube Q, and thence downwardly between this tube and 30 the tube N, the air passing thence into the passage D around the annular reflector, and being eventually delivered into the inclosed air-chamber around and below the fount E, whence it is delivered to the burner, as previously 35 described.

The flange R' serves to deflect the wind and dust which sweep along the roof of a car when in motion, and thus protect the air-inlet passages.

40 As heat and cold will expand and contract the metal somewhat, a small space is allowed between the extension-tube K and the guide-tube L, which allows an easy telescoping joint at this point. Any air which may enter 45 through this joint from below will be led upwardly to a point where it rises up with the exhaust-air or may go downwardly with any unusual pressure of the feed-air.

The overhanging tube N is made of larger 50 diameter than the extension-chimney K and its guide, and, as before stated, surrounds the upper end of both, and within this tube the feed-air and exhaust-air may unite, thus acting as a sort of counterbalance to counter- 55 act any excessive air-pressure from the outside.

The three air-channels previously described have distinct uses. The outer one is for the admission of the feed-air, the inner one is for 60 the escape of the exhaust-air and products of combustion, while the intermediate one serves as a point where the currents of feed and exhaust air both meet.

In Fig. 2 I have shown the application of 65 my invention to incandescent and Argand gas-burners in which the lower part of the burner is inclosed in a casing into which the

feed-air is admitted, as shown at D. From this chamber or casing part of the air mingles with the burning gas necessary for the incandescent light. The chimney G is supported in the usual manner by elastic springs I, resting upon the soft base or washer H, upon the chimney-holder or skirt a of the burner, covering the air-chamber into which the feed-air is admitted through the passage D. From this chamber air passes up within the chimney and exterior to the burner through openings between the supporting ribs or bars S of the chimney-base. Gas is admitted through 70 the pipe T, which has an extension-tip T', delivering into the perforated convex hood U, from which the gas escapes through the perforations into the suspended mantle V. Around the base of the tubular tip T' is an 75 inclosing hood W, which is open at the bottom to allow air to enter it from the air-chamber, and the tube T' has openings X made in the side within this hood, so that the air may 80 enter the tube T' and flow upwardly with the gas with which it is thus mixed and delivered with the gas through the perforated hood U 85 to supply the burner.

Having thus described my invention, what I claim as new, and desire to secure by Letters 90 Patent, is—

1. In a lamp-fixture, the combination, of a body consisting of a hollow vertical or side reflector, the extension-chimney to which it is connected, said body having feed and exhaust 100 passages and an air-chamber, open on top, a removable fount, having its lower part fitting into and over the said air-chamber and provided with a burner, and a glass chimney fitted to the burner and having its upper part 105 fitting within the chimney extension.

2. In a car side lamp-fixture, the combination, of a body consisting of a vertical or side reflector having an air-passage behind the reflecting-surface, said body being without 110 glass casing in front or surrounding the reflector, and having its lower portion projecting inside of the car and formed with an air-chamber in communication with the air-passage, and open on top, a removable fount to 115 be fitted into the open top of said air-chamber, and a burner and chimney carried by the fount.

3. In a lamp-fixture, the combination, of the body consisting of a vertical or side reflector having an air-passage behind the reflecting-surface said body having its lower portion 120 projecting into the car-body and forming an air-chamber in communication with said passage, a chimney extension and means for supplying air to said passage, the fount adapted to be fitted within the open top of the air-chamber so that its lower portion is inclosed 125 thereby, a burner and a glass chimney to protect the flame and conduct the draft from the 130 burner into the chimney extension.

4. In a lamp or lantern fixture, the combination, of a body consisting of a vertical or side reflector having an air-passage behind the re-

flecting-surface and having its lower portion projecting into the car and formed with an air-chamber, open on top, a removable fount adapted to be inclosed by said chamber, a
5 burner provided with a skirt adapted to fit upon the open top of the air-chamber and a glass chimney to be fitted to the burner.

In witness whereof I have hereunto set my hand.

EMILE BOESCH.
